UNITED STATES PATENT OFFICE.

PEHR CHRISTIANSSON, OF SCRIVEN, MINNESOTA.

NAILLESS HORSESHOE.

SPECIFICATION forming part of Letters Patent No. 715,021, dated December 2, 1902.

Application filed May 6, 1902. Serial No. 106,120. (No model.)

To all whom it may concern:

Be it known that I, PEHR CHRISTIANSSON, a citizen of the United States, residing at Scriven, in the county of Douglas and State 5 of Minnesota, have invented certain new and useful Improvements in Nailless Horseshoes; and I do hereby declare the following to be a full, clear, and exact description of the invention, such as will enable others skilled in the 10 art to which it appertains to make and use the same.

My invention has for its object to provide a nailless horseshoe of improved construction; and to this end it consists of the novel 15 devices and combinations of devices herein-after described, and defined in the claims.

The invention is illustrated in the accompanying drawings, wherein like characters indicate like parts throughout the several 20 views.

Figure 1 is a plan view of a horseshoe embodying the several features of my invention. Fig. 2 is a transverse section on the line $x^2 x^2$ of Fig. 1. Fig. 3 is a side elevation of the 25 horseshoe; and Fig. 4 is a view in side elevation, showing the so-called "spacing-link" of the shoe removed from working position.

The body of the shoe is made up of two sections a and b , pivotally connected at c , 30 which pivot is located at one side of the toe-calk. Both sections of the shoe are provided with upwardly and inwardly extended hoof-engaging lugs or ears d , provided on their inner faces with sharpened lips or detents e , 35 which are adapted to be pressed into the horse's hoof and to thereby give the lugs or ears d greatly-increased holding efficiency.

The character f indicates the toe-calk and the character g the heel-calks. The toe-calk 40 f is shown as provided with two rectangular stems or shanks f' , which fit in suitable seats formed in the toe portion of the shoe-section a . The heel-calks g are provided with similar rectangular stems or shanks g' , which fit 45 in suitable seats formed in the heel portions of the shoe-sections a and b . To securely but detachably hold the calks f and g in working position, screws f^2 and g^2 , respectively, are passed through suitable coincident per- 50 forations in the shanks f' and g' and in the body of the shoe.

To hold the pivoted sections of the shoe in the desired adjustment to keep the clamping lugs or ears d tightly pressed onto the horse's hoof, I provide a so-called "spanning" or 55 "spacing" link of novel construction. Of the parts of this link the character k indicates a short bar, which at one end is provided with a flattened or angular shank k' and at its other end is provided with a hook k^2 , which 60 engages the eye k^3 of a screw k^4 . The screw k^4 works with screw-threaded engagement in a seat b' of the shoe-section b , and the shank k' of the bar k fits closely within a seat a' of the shoe-section a . A machine-screw k^5 65 works loosely through that portion of the shoe-section a which is directly in line with the seat a' and is screwed into the shank k' of the bar k .

The manner of securing the shoe to a horse's 70 hoof is as follows: First the screw k^5 is removed, and the bar k is disconnected from the shoe-section a . The shoe is then placed on the horse's hoof, and the lugs or ears d are bent to fit the bevel or flare of the hoof. 75 Then the screw k^4 is turned so as to give approximately the proper projecting length to the link to properly space the sections of the shoe. The shank k' of the bar k is then inserted into the seat a' , and the screw k^5 is 80 then applied, as shown and described, and is screwed up until the lugs d of the shoe are tightly drawn against the hoof and the detents e embedded in the hoof. This being done, the shoe is securely fastened to the hoof 85 and in such manner that while it may be readily removed at will it will not become accidentally loosened.

The shoe above described is of small cost, has few parts to get out of order, and is effi- 90 cient for the purposes had in view.

It will of course be understood that the shoe above described is capable of considerable modification within the scope of my invention as herein set forth and claimed. 95

What I claim, and desire to secure by Letters Patent of the United States, is as follows:

1. The combination with pivotally-connected body-sections of the shoe, having clamping lugs or ears for engagement with the hoof, 100 of a spacing-link formed by hinged sections, one of which has screw-threaded engagement

with one of the shoe-sections, and the other of which is detachably securable to the other shoe-section, substantially as described.

2. The combination with the shoe-sections *a* and *b* pivotally connected at *c* and provided with the clamping ears or lugs, of the spacing-link made up of the hinged sections *k* and *k'*, the former having the shank *k'* fitting a seat in the shoe-section *a*, and the latter working with screw-threaded engagement

with a seat in the section *b*, and the screw *k*⁵ working loosely through a seat in said shoe-section *a* and screwed into the shank *k'* of the section *k*, substantially as described.

In testimony whereof I affix my signature ¹⁵ in presence of two witnesses.

PEHR CHRISTIANSSON.
